NONRESONATING TRANSFORMER

Alexis Panov and Moses Lipkovski, Moscow, Union
of Soviet Socialist RepublicsApplication May 9, 1939, Serial No. 272,678. In
the Union of Soviet Socialist Republics July
29, 1938

1 Claim. (CL 175—356)

This invention relates to improvements in non-resonating transformers in which the phenomenon of resonance is obviated by means of superimposing on the electrostatic field of a transformer winding the electrostatic field of an independent capacity potential divider connected to the beginning of the transformer winding.

According to this invention such a superimposition may be carried out in several different ways.

In the appended drawing Figs. 1, 2, 3, 4, 5, 6 and 7 show diagrammatically different modes of carrying out this invention.

In the embodiment according to Fig. 1, 1 designates sections of the transformer winding, 2 is a capacity potential divider composed of a series of condensers, 3 are potential distributing plates in the form of insulated flat metal washers connected to respective points of the potentiometer 20 and arranged between the transformer coils.

In the embodiment according to Fig. 2 the plates of the capacity potentiometer 2 have the form of insulated flat discs arranged between the coils 1 of the transformer.

According to Figs. 3 and 4 the capacity potentiometer comprises condensers 2 having the form of cylinders encircling the coil 1 and are capacitatively coupled one to the other.

Each of Figs. 5, 6 and 7 shows further modifications of Figs. 1, 2 and 3 respectively said modifications consisting in that for the purpose of eliminating the electrostatic flux passing from the current carrying system directly to earth, and, consequently eliminating the increase of potential difference between coils and the change of voltage distribution inside the coils themselves, due to this capacity earth current, metal guard rings 4 are used to screen the coils 1 radially, each guard ring being connected to respective 40 points on the electrostatic potentiometer.

The invention has many advantages over the well known transformers having no such capacitative protection. For instance in the transformer according to the invention there is no conductive connection between the protective device and the winding except at one end, so that the puncture of one condenser does not cause a short circuit in the coil.

Inside separate coils the capacity distribution of the voltage is improved. Thus, local distortions in voltage distribution are diminished. The invention renders it practically possible to double the protection of the winding.

All these advantages of the invention permit increasing the number of objects which can be made nonresonating.

As such may be mentioned transformers having delta connected windings, and three-phase transformers having the protective condensers arranged in the channels between the coils.

In the last case the proposed arrangement leads to a simple and compact structure, all transformer windings being open for protection, and the winding being easily accessible.

We claim:

A nonresonating transformer comprising, coils connected in a series circuit relation, a capacity potential divider capacitively associated with said coils and conductively connected to one end of the series of coils, said capacity potential divider comprising cylindrical condenser plates encircling the coils and capacitively associated with each other, insulated discs arranged between the coils conductively connected to said condenser plates, rings arranged to screen the coils with respect to ground, and said rings being connected to said condenser plates.
